UNITED STATES PATENT OFFICE.

EDWARD J. CHAPMAN, OF MERRIMAC, MASSACHUSETTS.

CHEMICAL FIRE-EXTINGUISHER.

SPECIFICATION forming part of Letters Patent No. 673,383, dated May 7, 1901.

Application filed December 24, 1900. Serial No. 40,960. (No model.)

To all whom it may concern:

Be it known that I, EDWARD J. CHAPMAN, a citizen of the United States, residing at Merrimac, in the county of Essex and State of 5 Massachusetts, have invented a new and useful Chemical Fire-Extinguisher, of which the following is a specification.

This invention relates to fire-extinguishers, and more particularly to chemical-mixing fire-extinguishers; and the object of the same is to provide a fire-extinguisher of this nature which is safe and reliable in use and will not explode, readily charged, discharged, and recharged without injury to any part of 15 the apparatus, and one having a simple automatic operation, a combined handle and discharge-nozzle, and means for preventing passage of the acid directly into the said nozzle and for preventing corrosion of the parts.

20 The invention consists in the construction and arrangement of the several parts, which will be more fully hereinafter described and claimed.

In the drawings, Figure 1 is a perspective 25 view of a fire-extinguisher embodying the features of the invention. Fig. 2 is a transverse vertical section of the same. Fig. 3 is a detail perspective view of the acid-bottle-holding cage with the bottle therein and the 30 automatically - operating cap for the same. Fig. 4 is a sectional elevation of the parts shown by Fig. 3 in inverted position and the cap released from the neck or mouth of the bottle.

35 Similar numerals of reference are employed to indicate corresponding parts in the several views.

The numeral 1 designates the shell or casting, preferably constructed of the best hard 40 cold-rolled copper, with the seams overlapped and closely riveted and sweated with a good quality of solder, the crown 2 and bottom 3 being spun into the shape shown and said crown having a cap 4 riveted and sweated 45 thereto. All of the foregoing-named parts are fully coated with non-corrosive material to prevent injury thereto by the chemicals and conform in general construction and dimensions to the standard requirements of insurance companies.

To the bottom 3 a stand 5 is secured, and

comprises a plurality of supports 6, preferably formed of cast-brass and secured to the said bottom, at the joint thereof, by suitable rivets, the lower terminals of the supports 55 being apertured and having a round bar 7 passed therethrough and firmly fastened, the said bar forming a handle or convenient means of gripping the bottom portion of the extinguisher when using the latter. 60

The cap 4 is annular and has an upper screw-threaded seat 8 to receive a plug 9, of suitable metal, preferably cast-brass, having a central outlet-opening 10 with a screw-threaded wall. Immediately below the seat 8 the 65 cap is formed with an inwardly - extending horizontal seat 11, on which is disposed an annular washer 12, directly under the screw-threaded joint of the plug with the cap, to prevent corroding by the chemicals or acids of 70 the threads of said joint, another shoulder 13 being formed in the cap inwardly from and below the plane of the seat 11 for a purpose which will be presently set forth. The outer lower portion of the cap is offset at an outward angle, as at 14, to receive and have riveted thereto the upper terminal of the crown 2, the rivets 15 being arranged at an inward angle and upset against the bottom portion of the cap, as shown. 75

Within the opening 10 of the cap the lower tubular neck 16 of a combined handle and nozzle is securely fastened, first, by a single thread and then locked against movement by the insertion of a plurality of pins 17, one of 80 the latter being shown in dotted lines in Fig. 2, and after such insertion of the pins the joint is treated with lead to seal the same. The said neck unobstructedly communicates with a curved outlet-conduit 18, having a normal 85 vertical direction and continuing into a reversely-curved nozzle extremity 19, with a forwardly - projected terminal having a nozzle-tip 20 removably mounted therein. From the rear upper portion of the neck a curved grip 90 21 projects and merges into an upper horizontal enlarged portion 22, that connects with the conduit 18, and with the latter said grip forms a substantially elliptical hand-loop for transporting the extinguisher from one point 95 to another and to conveniently direct the nozzle-tip when the entire device is tilted or other- 100

erwise arranged to permit the contents to flow therefrom. This combined structure has many advantages and among others may be particularly mentioned that it does away with 5 the usual rubber hose, is strong and durable and cannot destroy itself, as in the case of rubber hose after standing for a length of time, and it relieves any tendency of any part of the extinguisher to explode when operated.

10 The entire device can be held by both hands and carried from one place to another while being operated, and a steady stream can be obtained therefrom and directed to any point except those obviously dangerous positions 15 where an operator would not stand directly overhead or under foot. The conduit furnishes a free and clear outlet and prolongs the stream or flow a greater length of time than in some previous machines using the same 20 amount of fluid. The nozzle-tip is detachable and non-corrosive, and the plug 9 can be easily turned out when badly stuck by the insertion of a wrench or other suitable implement through the looped portion of the combined 25 device.

The upper angular ends of a plurality of arms 23, forming a cage 24, are hung on the seat 11 of the plug 9, and in the cage an acid-bottle 25 is mounted and preferably of eight- 30 ounce capacity and provided with an upper wide outlet-neck 26, having a ground rim 27. Above the neck of the acid-bottle a hollow substantially spherical acid non-porous cup 28 is fixed and has depending guards 29 to 35 hold the bottle in place and against movement in the cage, and also extending downwardly from the center of the upper portion of the cup is a pin 30. Movable mounted in relation to and guided by the said pin is a 40 lead cap 31 of solid hemispherical form and having a vertical opening 32 in the upper portion thereof, into which the pin extends. Extending transversely across the lower inserted portion of the neck 16 of the combined 45 handle and nozzle is a guard 33, which keeps the cup from slipping from its place when operated, and between the said guard and the top of the cup a reticulated partition 34 is positioned and covers the outlet from the shell 50 or casing to serve as a screen to prevent the crystals or foreign matter from passing into the discharge-conduit.

In the operation of the device the body or shell is tilted or turned at an angle, so that 55 the cap 31, which normally bears on the ground rim of the acid-bottle 25, moves off from the said rim and permits the acid to mingle with the fluid that is placed in the said shell. By using a large-neck bottle, as 60 shown and set forth, a quick action can be secured and an excess of carbonic-acid gas generated and simultaneously injected with the liquid in the shell, the said liquid being a soda solution. The extinguishing liquid, 65 composed of the soda solution and the acid from the bottle, becomes thoroughly formed before passing into the discharge-conduit,

and, as before indicated, said conduit and its nozzle-tip will materially facilitate the direction of the liquid on the fire. After the service of the extinguisher is no longer needed it is righted and the cap gravitates to its normal position and again closes the bottle. 70

A non-corrosive material will be applied to all the parts where necessary to protect them, 75 and other minor incidentals will be supplied at points where required to render the extinguisher practically complete, and while the preferred form of the device has been shown and described it is obviously apparent that 80 changes in the size, form, proportions, and minor details of the several parts may be made without departing from the principle of the invention.

Having thus described the invention, what 85 is claimed as new is—

1. In a chemical fire-extinguisher, the combination of a body or shell for holding an alkaline liquid, a cap in said body with an opening therethrough, a plug removably mounted 90 in said cap and having outlet means, a cage suspended from said cap and held in place by the plug, an acid-containing receptacle movably mounted in the cage with its outlet portion uppermost, an acid -cup mounted 95 above and rigidly held within and by the cage and provided with a central projecting portion, and a weighted cap of solid form having a lower horizontal face to contact with the upper open portion of said receptacle and 100 having an upper opening to loosely receive the projection of the cup.

2. In a chemical fire-extinguisher, the combination of a body or shell for holding an alkaline liquid, an acid-containing receptacle 105 suspended or hung from the interior top portion of the body or shell and provided with an upper wide - open portion or outlet, an acid -cup mounted above and surrounding said upper open portion of the said receptacle and having a depending pin, and a weighted cap of solid form having a lower horizontal face to contact with the upper open portion of the receptacle, the said cap also having an upper opening to loosely receive the 115 pin of the cup.

3. In a chemical fire-extinguisher, the combination of a body or shell for holding an alkaline liquid, a cage suspended from the upper inner portion thereof, an acid-containing 120 receptacle supported by the cage and having an upper outlet, a substantially hollow hemispherical acid-cup in the cage over the upper portion of the receptacle, a weighted cap movable in relation to and within the cup 125 and having a flat face to loosely bear on the upper open portion of the receptacle, an outlet device at the top of the shell, a guard against which the cup indirectly bears to hold said cup in place in the cage, and a reticulated partition between the guard and cage and the cup in the latter and the outlet device. 130

4. A fire-extinguisher having an upper clos-

ing-plug with a combined handle and nozzle connected thereto, the latter being in the form of a hand-loop with the front portion tubular and continued above into a forwardly-curved nozzle extremity, and a forwardly-projecting nozzle in the upper terminal of said nozzle extremity.

In testimony that I claim the foregoing as my own I have hereto affixed my signature in the presence of two witnesses.

EDWARD J. CHAPMAN.
